(57) **CLAIM**

The ornamental design for a tire press horizontal cross-member, as shown and described.

DESCRIPTION

FIG. 1 is a perspective view of a tire press horizontal cross-member's position in a tire press assembly;

FIG. 2 is a front elevational view of a tire press horizontal cross-member showing my new design;

FIG. 3 is a top plan view thereof;

FIG. 4 is a bottom plan view thereof;

FIG. 5 is a perspective front view thereof;

FIG. 6 is a perspective rear view thereof;

FIG. 7 is a sectional view taken in the direction of the arrows on line 7-7 of FIG. 3;

FIG. 8 is a side elevational view taken from the right of FIG. 2; and,

FIG. 9 is a rear elevational view thereof.

The broken lines in the drawings depict unclaimed environmental subject matter.
